UNITED STATES PATENT OFFICE

2,202,005

SHOE MACHINE

Eric A. Holmgren, Lynn, Mass., assignor to United
Shoe Machinery Corporation, Borough of
Flemington, N. J., a corporation of New Jersey

Application November 15, 1937, Serial No. 174,542

68 Claims. (Cl. 12—67)

This invention relates to machines for operating upon shoes and is illustrated as embodied in a machine of the type shown, for example, in United States Letters Patent No. 1,614,836, granted January 18, 1927, on an application filed in the name of George Goddu, and No. 2,045,577, granted June 30, 1936, on an application filed in the name of Benjamin B. Blanchard. Such machines are designed for butting the welt of a welted shoe preparatory to the sole laying operation and for fastening the welted margin of the upper to the insole in the region of the heel breast line. Such machines include welt engaging devices for positioning the welt ends during the butting operation, cutters for butting the welt comprising stationary shear members and knives movable lengthwise of the shoe to skive and shear off the welt ends and fastening inserting means for securing the upper in the region of the welt butts to the insole.

In preparing the bottom of a Goodyear welt shoe for the sole attaching operation it is required that the welt ends be butted in such a manner that they are inconspicuous in the finished shoe. This is usually accomplished by cutting off the ends of the welt on a long bevel, and the longer the bevel the less conspicuous are the welt ends in the finished shoe.

It is an object of this invention to provide welt butting mechanism which is capable of making a welt butting cut which is longer than that produced by welt butting machines heretofore employed. Accordingly, a feature of the invention consists in the provision in a welt butting machine having welt butting knives which move longitudinally of the welt during the cutting stroke and in their rest position are located away from the shoe bottom and opposite the breast line portion of the shoe, of means for moving the knives from their rest position toward the toe end of the shoe and toward the shoe bottom to their cutting position. This organization affords the longest cutting stroke which can possibly be obtained without bringing the backs of the knives against the sharply inclined shank portions of women's high-heeled shoes. In moving the knife from its rest position to the beginning of its cutting stroke it is first moved toward the toe end of the shoe in an inclined path to an intermediate position, then from its intermediate position to its cutting plane, the latter movement of the knife being directly toward the shoe bottom without any forward component of movement in order to render it impossible for the knife to move the shoe forward during the latter

part of its preliminary movement. In the illustrated machine each of the knives is mounted in a rocker which moves the knife toward and from its cutting plane, and each rocker is supported on a carrier which is moved first forwardly to position the knife for the beginning of its cutting stroke, then rearwardly to effect the cutting stroke.

It is an object of the invention to provide in a welt butting machine means for flattening the ends of the inseam in order to provide a smooth even shoe bottom in the region of the heel breast line for the reception of the outsole, and it is a further object of the invention to provide means for supporting the shoe for the inseam flattening operation. Accordingly, the illustrated machine is provided with a suitable work support and in accordance with a feature of the invention mechanical means is provided for moving the support heightwise of the shoe to position the shoe at a predetermined elevation and the shoe is held at that elevation during the inseam flattening operation by hydraulic means which holds the support against return movement. It is to be understood that the utility of the illustrated work supporting mechanism is not limited to welt butting machines having means for flattening the end portions of the inseam.

In the illustrated machine the upward movement of the work support is arrested by engagement of the shoe bottom with a member for positioning the shoe heightwise in the machine, and the hydraulic locking means holds the shoe in engagement with said shoe bottom engaging member during the inseam flattening operation. The illustrated work support is constructed and arranged to permit free movement of the supported shoe in any direction in a plane common to the rear portion of the shoe bottom, thereby to permit the shoe to be moved lengthwise into the machine and to be adjusted widthwise by welt supporting members constructed and arranged to engage the supported shoe within the welt crease.

In accordance with a further feature of the invention the shoe support is constructed and arranged to receive any one of a plurality of shoe supporting members, and the support is provided with means for retaining said members in shoe supporting position. As herein illustrated, two such shoe supporting members are provided one of which is provided with a last pin while the other has a horizontal corrugated upper surface for engaging the cone of a last. When the latter shoe supporting member is employed it is unnec-

essary for the shoe support to have any movement other than heightwise of the shoe and, accordingly, a further feature of the invention consists in the provision in a shoe machine having a work support freely movable lengthwise and widthwise of the shoe, of means for locking the shoe support against such lengthwise and widthwise movement.

In the use of the illustrated machine, it is necessary that the crease finders and shear members be properly positioned heightwise, widthwise and lengthwise in the machine, and also that the shear members, which become worn, and the crease finders, which it may be desired to change to accommodate different types of work, be readily replaceable. It is, therefore, an object of this invention to provide a machine organization which permits such heightwise, widthwise and lengthwise adjustments of the shear members and crease finders, and also facilitates the replacement of these elements. Thus, in accordance with a further feature of the invention, the shear members and crease finders are mounted in removable heads supported on carriers which are arranged to have heightwise, lengthwise, and widthwise adjusting movements.

It is proposed to employ shear members which retract to provide clearance for driving fastenings, as in the machine of the Blanchard patent above referred to, and it is also proposed to provide welt-supporting crease finders which may be retracted to prevent disfiguration of the upper engaging surface of the welt during the inseam flattening operation. With the above objects in view, a further feature of the invention consists in the provision of a member in which both the shear member and the crease finder are mounted for operative movement relatively to said member widthwise of the shoe.

In the manufacture of Goodyear welt shoes there is a tendency for the end portions of the inseam to work outwardly toward the edge of the shoe bottom and when this occurs the outsole stitcher often finds it necessary to carry the outseam outwardly in the region of the ends of the inseam in order to avoid the inseam stitches, and in doing so the outseam is sometimes carried outwardly too far and part of it is cut away in the trimming of the sole margin. It is, therefore, an object of the present invention to work the end portions of the inseam inwardly before the welted margin is secured to the insole. In the illustrated machine, such inward urging of the inseam is effected by engaging the welt between gripper members which grip a substantial extent of the width of the welt and moving said members inwardly together toward the center of the shoe bottom. The illustrated gripper members are the welt supporting crease finders and members through which fastenings are driven to secure the welted margin to the insole.

To augment the inward movement of the end portions of the inseam and to flatten the end portions of the inseam substance, thereby to provide a smooth and even shoe bottom in the region of the heel breast line, there is provided, in accordance with a further feature of the invention, means constructed and arranged to operate against the members through which the fastenings are driven to pound said members against the shoe bottom. As herein illustrated, the direction of the pounding action is downwardly toward the shoe bottom and widthwise of the shoe toward the center of the shoe bottom, thereby

bending the end portions of the inseam substance inwardly against the insole.

It is a further object of the invention to secure the welted margin in the region of the welt butts to the insole by means of a plurality of fastenings which may be driven in different positions widthwise of the shoe bottom in order to obtain the most effective attachment of the upper and the welt to the insole. With this object in view a further feature of the invention consists in the provision of a plurality of fastening driving actuators and means for operating the actuators comprising a driven slide which is operatively connected to one of said actuators which, in turn, is operatively connected to the other actuator, said connections being constructed and arranged to permit individual adjustment of the actuators widthwise of the shoe. It is to be understood that the utility of this feature of the invention is not limited to welt butting machines.

In machines having tack driving mechanism the removal of tacks which become fouled in the tack pockets is a source of annoyance to the operator and it is an object of the present invention to make it easier for the operator to remove fouled tacks. Accordingly, another feature of the invention consists in the provision in a shoe machine provided with tack driving mechanism, of tack-holding members which by their engagement with each other provide a pocket for holding a tack for the driving operation, one of which members is readily accessible, and means for moving said member from its tack holding position to expose a tack in said pocket and to permit the tack to be removed from the machine. In the illustrated machine the means for moving said member is a handle extending from the tack driver guide into a position in which it is easily reached for manipulation by the operator.

In order to remove the shoe from the machine during the interval between the retraction of the operating parts and their return to their initial positions, an ejector engages the shoe and moves it away from the operating parts of the machine. The member for ejecting the shoe also operates during the welt butting operation to hold the shoe against movement in the direction of the welt butting cut. The illustrated ejector is movable with the shoe lengthwise thereof as the shoe is brought into position to be operated upon and is arrested to position the shoe for the welt butting operation by an adjustable abutment. The illustrated ejector operates to remove the shoe from the machine during the interval after the shear members have been retracted and before they are returned to their initial position.

These and other features of the invention will now be described with reference to the accompanying drawings and will be pointed out in the appended claims.

Fig. 40 is a detail view of part of the mechanism illustrated in Fig. 39;

Fig. 41 shows a shoe in the machine and indicates diagrammatically the path of movement of the welt butting knives;

Figs. 42 to 45, inclusive, are cross-sections of a shoe in the machine illustrating certain operating parts at successive stages in the operation of the machine;

Fig. 46 is a plan view of the rear portion of a shoe in the machine indicating diagrammatically the preferred operating positions of the tack driver guides thereon; and

Fig. 47 is a cam chart.

The illustrated machine is provided with a jack 15 for supporting an inverted shoe in operative position and is provided with crease finders for supporting the end portions of the welt in position for the butting operation. As in the machine of the Goddu patent above referred to, the ends of 20 the welt are butted simultaneously by knives which move rearwardly in a horizontal plane and cooperate with stationary shear members or anvils to shear off the waste ends of the welt and the butted ends of the welt are secured to the insole 25 by tacks. The operating parts of the machine are mounted on carriers which swing on vertical shafts in the machine head for movement toward and from the longitudinal median line of the shoe to move the parts to and from operative 30 position.

The illustrated shoe supporting jack comprises a cylinder 34 within which there is slidably mounted a work supporting post 36 (Fig. 4). The illustrated work support is constructed and arranged for swinging movement in a vertical plane extending from front to back of the machine to bring the shoe into engagement with welt supporting members or crease finders 38 (Fig. 1) arranged at opposite sides of the shoe. The work support is moved upwardly after the shoe has been brought into engagement with the crease finders to press the shoe against a holdown member or bar 40. In order to permit the shoe to be positioned widthwise thereof by the crease finders 38, 45 the work support is constructed and arranged for a slight transverse swinging movement. Referring now to Figs. 2 and 3, the cylinder 34, which is the lower portion of the work support, is pivotally mounted at its lower end between arms 42 at 50 the forward end of a carriage 44 which is swiveled on a lever 46 on a cross shaft 48 journaled in the machine standard. As illustrated in Fig. 2, the carriage 44 has upwardly extending end portions 50 and 52, the latter of which extends into an 55 opening in the lever. The end portions 50 and 52 have studs 54 and 56 which are swiveled in a lengthwise bore in the lever 46. For limiting the transverse movement of the work support, the lever 46 has downwardly extending abutment 60 members or lugs 58 (Fig. 5) the inner surfaces of which are spaced a short distance from the opposite sides of the carriage 44. It will be understood that the extent of transverse swinging movement of the work support is determined by 65 the extent of widthwise movement of the carriage 44 permitted by the lugs 58. For yieldingly holding the work support midway between the extremes of its transverse swinging movement, the carriage 44 has mounted in a bore extending 70 laterally thereof two thimbles 60 the openings of which are arranged to receive a compression spring 62 which urges the thimbles away from each other and into engagement with plates 64 secured to the lower portion of the carriage. The 75

plates 64 engage the lower portion of the thimbles 60 while the upper portions of the thimbles engage the lugs 53 on the lever 46 and yieldingly position the carriage 44 centrally of the space 5 between said lugs, as illustrated in Fig. 5. For limiting the forward movement of the work support a link 66 (Fig. 2) is pivotally mounted between lugs projecting rearwardly from the cylinder 34 and is provided at its rear with an openended slot 68 through which extends a cross shaft 78 mounted in the machine standard. The slot 68 is closed by a grooved plate 72 which is yieldingly held against the rear end face of the link 66 by a spring 74 mounted in a counterbore in an 10 upward extension 76 of the link and arranged to operate against a flanged nut 77 on a screw 78 which is threaded into the upper portion of the plate 72. The spring 74, acting on the plate 72, yieldingly arrests the forward swinging movement 15 of the work support. As illustrated in Fig. 4, the work support has at its upper end a sleeve 80 which carries a pin 82 which projects upwardly for engagement within the pin hole of a last. The sleeve 80 is slidably mounted on the post 36 and 20 is provided with a downwardly extending pin 84 which is slidably mounted in a hollow screw 86 which is threaded into the upper portion of the post 36. The pin 84 engages the upper end of a 25 sliding block 90 in a socket 88 in the post, which block is pressed upwardly by a light spring 92 mounted in the socket 88. The spring 92 positions the supported shoe slightly above the proper elevation for registration with the crease finders and as the work support is swung rearwardly the 30 heel-seat portion of the shoe bottom engages the upwardly curved forward portion of a hold-down hereinafter described and is cammed downwardly thereby to position it at the proper elevation. During the upward movement of the work support, after the shoe has engaged the hold-down, the post 36 moves upwardly through the sleeve 80 until it engages the head at the upper end of the sleeve and provides a positive support for the shoe. For holding the sleeve 80 against turning 35 movement on the post 36 an arm 96 is pivotally mounted on a block 98 projecting forwardly from the post 36 and is provided with a detent 100 which extends through a slot 102 provided in the sleeve 80 and into a groove in the post. The arm 96 is yieldingly held against the sleeve 80 by a 40 spring 104 mounted in a bore in the block 98 and arranged to engage a downward extension 106 of the arm 96. For holding the post 36 against turning movement in the cylinder 34 the block 98 is extended downwardly into a slot 108 (Fig. 1) in the upper portion of the cylinder.

In operating on shoes the uppers of which do not extend above the cone of the last, the last may be mounted on the work support illustrated 45 in Fig. 6 and the work supporting assembly may be locked in substantially upright position against forward and rearward swinging movement. In this case the shoe is moved rearwardly to bring it into engagement with the crease finders while 50 the work support remains at rest. It will be understood that the last pin unit illustrated in Fig. 4 may be removed from the cylinder 36 by merely disengaging the arm 96 from the sleeve 80 and the unit illustrated in Fig. 6 may be 55 mounted in place of the last pin unit on the post 36. In place of the last pin element illustrated in Fig. 4 the unit illustrated in Fig. 6 is provided with a block 110 the upper surface of which is corrugated for gripping engagement with the 60 cone of the last, said corrugations extending 65

widthwise of the shoe and holding it from lengthwise movement. When the work supporting unit illustrated in Fig. 6 is employed it is desirable to 70 adjust the post 36 for different heights of last in order that the block 110 may be located in work supporting position since the block 110 has no movement on the post 36 but rests at all times on the screw 86 at the upper end of the post. For so adjusting the post 36 the cylinder 34 is internally threaded at its lower end for the reception 75 of a hollow screw 112 (Fig. 4) through which a stem 114 extends downwardly from the lower end of the post. The screw 112 is held in a fixed position on the stem 114 between washers 116 which are held in place by lock nuts. The screw 112 is 80 secured in adjusted position by a spring-pressed friction plug 117 having teeth which fit into the 85 threads of the screw.

For locking the work support against forward and rearward swinging movement the illustrated 90 machine is provided with a locking member 118 (Figs. 2, 4 and 7) which is secured to the shaft 70 and is provided with parallel arms 120 (Fig. 7) which engage opposite sides of the link 66 when the locking member is swung into locking position, 95 as illustrated in Fig. 7. At its forward end one of the arms 120 is provided with a hollow boss 122 within which is slidably mounted a locking pin 124 which, when the locking member is in locking position, extends through a bore in the 100 link 66 and holds the link against lengthwise movement. For moving the locking pin to and from locking position it is provided with a handle 126 in the form of a square head at the lower end 105 of a pin extending from the locking pin downwardly through a lengthwise slot in the boss 122. For holding the locking pin in locking position a latch pin 128 is mounted in the boss 122 for engagement within a groove 130 in the pin. The arms 120 are arranged to fit closely against the 110 opposite sides of the link 66 when it is in locking position in order to hold the work support against transverse movement, such movement of the work support not being required when the unit illustrated in Fig. 6 is employed since the shoe is free 115 to move widthwise thereof relatively to the work support.

For imparting vertical movement to the work support to press the shoe upwardly against the hold-down the illustrated machine is provided 120 with a cam 132 (Fig. 8) which is keyed to a cam shaft 134 and is arranged to operate a lever 136. The lever 136 is connected by a link 138 to an arm 140 pinned to a rock shaft 141 which also carries a horizontal arm 143 which is pivoted to a member 142 which carries a vertical rod 144 having an enlarged lower portion 146 which carries a sleeve 148 which is pivotally mounted between rearwardly extending arms of the lever 146. The sleeve 148 is yieldingly held in its position illustrated in Fig. 3 between springs 150 and 152 which engage washers 154 positioned, respectively, above and below said sleeve and normally held by the springs against shoulders provided by the enlargement 146 of the rod 144. It will be understood that the spring 150 takes up the excess motion of the cam lever 136 after the upward movement of the work support has been arrested by the engagement of the shoe with the hold-down. For holding the work support against 150 downward movement during the pounding of the inseam the illustrated machine is provided with a hydraulic lock comprising a fluid reservoir or hollow cylinder 156 which is partially filled with fluid, a fixed hollow piston 158 on which the cylinder 152 155

der is slidably mounted, and a valve 160 at the lower end of a stem 162 which is slidably mounted in a hollow fixture 164 in the upper portion of the piston. Mounted in the fixture is a spring 166 which presses upwardly against a head 168 at the upper end of the stem 162 and holds the valve 160 in closed position. The cylinder 156 is supported by parallel arms 170 one of which is illustrated in Fig. 2, said arms being pivotally mounted in brackets 171 extending in opposite directions from the upper portion of the cylinder. At their lower ends the arms 170 are secured to a block 172 which is pivoted between the rear ends of the lever 46. During the downward movement of the rod 144 the cylinder 156 slides downwardly on the piston 158 and the fluid contained within the hollow piston 158 flows downwardly through a port 174 provided in a plug 175 at the lower end of the piston, the valve being held open during the greater part of the downward movement of the rod 144 by a ball-ended lever 176 which engages the head 168 of the valve stem. For operating the lever 176 the machine is provided with a lever 178 which swings about a fixed pivot 180 and is yieldingly urged in a counterclockwise direction, as seen in Fig. 8, by a spring 182. For controlling the operation of the lever 178 an arm 184 extends upwardly therefrom and carries at its upper end a roll 186 which travels on the arcuate surface of a downward extension 188 of the arm 143, said arcuate surface having its center at the pivot of the arm. During that portion of the operative movement of the arm 143 which occurs after the lever 46 has come to rest, the downward extension 188 of the bell-crank lever continues its downward movement until a recess 190 provided therein is positioned to receive the roll 186, thus permitting a counterclockwise movement of the lever 178 which lifts a link 192 pivoted to the lever 178 which, in turn, swings upwardly an arm 194 secured to a rock shaft 196 which carries the lever 176. As the lever 176 moves upwardly, the valve 160 is closed by the spring 166 on the stem 162 and the cylinder 156 is locked against upward movement, thus locking the work support against downward movement. If the machine is operated when there is no shoe on the work support a downward extension 198 of the block 172 engages an abutment 200 (Fig. 2) to limit the operation of the lever 46 which lifts the work support. During the latter part of the machine cycle after the operations on the shoe have been completed the arm 143 swings upwardly and the roll 186 moves out of the recess 190, causing the lever 178 to move in a clockwise direction to open the valve. During this initial movement of the arm 143 the lever 46 which operates the work-supporting assembly remains at rest but immediately after the valve opens the lever 46 begins to operate to return the work-supporting assembly and the cylinder 156 to their initial positions. If for any reason the fluid in the cylinder does not move freely through the port the movement of the arm 143 is taken up by the spring 152 (Fig. 2) which is mounted on the lower portion of the rod 144 and is confined between a nut 204 in the lower end of the rod and the washer 154 (Fig. 8) which is normally held by the spring 152 against the enlarged portion of said rod.

The holddown which positions the shoe vertically in the machine comprises a vertical bar 40 (Fig. 18) which is mounted for vertical movement on parallel arms 209 pivoted to the machine head. The holddown is urged upwardly by

a spring-pressed pin 211 which operates against an arm 213 to hold the bar 40 against a screw 215 which is adjustable to vary the vertical position of the holddown. A shoe-engaging plate 217 is pivoted to the lower portion of the bar 40. Said plate has an upwardly curved bottom face which causes the shoe to move downwardly into position to receive the crease finders as it moves rearwardly into the machine. The plate 217 is adjustable to provide clearance for the shanks of women's shoes by turning a screw 219 which is held against the bar 40 by a spring-pressed pin 221 mounted in the plate and arranged to act against the bar.

For skiving the welt in the region of the heel breast line and cutting off the waste ends of the welt the illustrated machine is provided with two knives 208 (Fig. 10) and two shear members or anvils hereinafter described. The knives 208 are mounted in knife holders 210 (Fig. 15) and are secured in the grooves provided in the knife holders by clamping screws 212 in the forward ends of the holders. The clamping screws operate against clamping plates 214 swiveled thereon and arranged to engage the knives and secure them in position in the V-grooves. Like mechanisms are provided for supporting and operating the knives and the following description is applicable to either one. Referring to Fig. 13 illustrating the knife 208 at the left of the machine and the mechanism for operating it, the knife holder 210 is illustrated as a rocker arm which is pivotally mounted at 216 to the forward portion of a slide 218 which is mounted in a bracket 220 extending downwardly from one of the tacker heads. Said heads are mounted for swinging movement on shafts 222 in forward extensions of the machine head. When the machine is at rest the welt butting knives are located above the welt ends of the shoe in the machine and somewhat above 40 their cutting elevation. At the beginning of the machine cycle the knives move toward the toe end of the shoe and downwardly to their cutting elevation, then rearwardly to perform the welt butting operation. Thereafter the knives move 45 upwardly to their initial elevation and then back to their initial position over the butted ends of the welt. The knives are never located forwardly of the point where the cutting stroke commences and consequently the knives will not strike 50 against the inclined shank portions of women's shoes during their movement preliminary to the cutting stroke. For operating the welt butting knives a disk 224 on the cam shaft has a cam path 226 within which travels a roll 228 mounted 55 on a vertical lever 230. The lower end of the lever 230 has pivoted thereto a swivel block 232 which is slidably mounted between lugs 234 extending downwardly from a slide 236. The rear portion of the slide is mounted in a T-way in a 60 fixed bracket 238 while the forward portion of the slide is in the form of a horizontal T-plate which is slidably mounted on gibbs 240 (Fig. 11) secured to opposite sides of a forward extension 242 of the machine head. The forward portion of 65 the slide 236 has a transverse groove 244 in its bottom surface within which are slidably mounted blocks 246 which are swiveled on the heads of screws 248 secured to inward extensions of the knife operating slides 218. Referring now to Fig. 70 13 illustrating the block 246 at the left of Fig. 11 and mechanism for operating the knife at the left of the machine, the slide 218 has mounted therein a slide 250, the slide 218 being provided with grooves (Fig. 11) for the reception of the 75

slide 250. The slide 250 is provided with a cam slot 252 within which is mounted a roll 254 pivoted to the rear end of the knife holder 210. Referring now to Fig. 14, the slide 250 is yieldingly held against movement in the slide 218 by headed friction members or plugs 256 which are mounted in a vertical bore in the slide 250 and are pressed against the slide 218 by a spring 258 mounted in the bore and arranged to engage the ends of the friction plugs. Projecting upwardly from the rear portion of the slide 250 is a lug 260 which, when the machine is at rest, is positioned in engagement with the rear end of a plate 262 secured to the swinging arm 220 which carries the slide 218. During the first part of the machine cycle the slide 218 is moved toward the toe end of the shoe, or to the left as seen in Fig. 13, and the slide 250 is held in its position illustrated in Fig. 14 by the engagement of the lug 260 with the plate 262 and the roll 254 on the knife holder 210 moves half way up the incline of the cam slot 252 provided in the slide 250. The upward movement of the roll swings the arm 210 in a counterclockwise direction, as seen in Fig. 13, and moves the knife downwardly into an intermediate elevation in which it is still somewhat above its cutting elevation and out of engagement with the bottom of the shoe. After the knife comes to the limit of its forward movement mechanism hereinafter described moves the slide 250 rearwardly, or to the right as seen in Fig. 13, to move the knife vertically downward into its cutting elevation. Thereafter the slide 218 is moved rearwardly to cause the knife to cut off the waste end of the welt. During the cutting stroke of the knife the slide 250 travels with the slide 218 and the knife is positively held against upward movement by the engagement of the roll 254 with the horizontal surface 264 of the cam slot 252. After the cutting stroke has been completed a lug 266 (Figs. 12 and 14) projecting upwardly from the central portion of the slide 250 engages a lug 268 projecting downwardly from the plate 262 arresting the slide 250. The rearward movement of the slide 218 continues after the slide 250 has been arrested, causing the roll 254 to travel down the incline of the cam slot 252 and raise the knife to its initial elevation. The rearward movement of the knife continues after it has been so elevated to provide clearance for the operation of the pounding and tacking mechanism and after these operations have been completed the knife moves forwardly to its starting position.

During the forward movement of the knives preliminary to the cutting stroke they are moved downwardly about half way from their initial elevation to their cutting elevation by mechanism above described. Before they start the cutting stroke the knives are moved vertically downward into cutting elevation by mechanism comprising a peripheral cam 270 (Fig. 13) formed in the disk 224 which engages a roll 272 pivoted to the rear end of a slide 274 the rear portion of which is supported by a fixed pin 276 which is slabbed off for engagement within a horizontal open-ended slot provided in the slide. The forward portion of the slide is supported by the forward extension 242 of the machine head and is positioned centrally of the width of the machine. The slide is moved forwardly or to the left as seen in Fig. 13, by a rise 280 in the cam 270, thereby imparting rearward or opposite movement to two slides 282 which are supported by the extension 242 of the head and are mounted in grooves provided in the arms 220 respectively

(Fig. 11). Each slide is provided with a shoulder 286 which engages the lug 260 on the slide 250 and moves the slide rearwardly or to the right as seen in Fig. 13, carrying the roll up the incline of the cam slot in said slide and into the forward portion thereof and swinging the knife holder counterclockwise to move the knife downwardly into its cutting elevation. For transmitting the forward movement of the slide 274 to the slides 282 the slide 274 is provided with two rows of rack teeth 288 (Fig. 10) which engage teeth 290 in the hubs of gear segments 292 mounted on the forward extension 242 of the machine frame and pivoted on washers 294 on the shafts 222, which washers, as illustrated in Fig. 15, support the weight of the arms 220. The gear segments 292 engage rack teeth 296 provided in the slides 282 and simultaneously move said slides rearwardly. As the cam roll 272 on the slide 274 (Fig. 13) rides down the rise 280 of the cam surface 270 a spring-pressed pin 298 mounted in a socket in an upward extension of the slide 274 acting against a fixed abutment 300 moves the slide 274 rearwardly, thereby moving the slides 282 forwardly and providing sufficient clearance between the lugs 266 on the slides 250 and the shoulders 286 in the slides 282 to permit the return of the slides 250 to their initial positions.

For laying the welt down flat against the crease finders to prepare it for the cutting operation, the illustrated machine is provided with two ironers, herein illustrated as L-shaped members 302 (Fig. 10) which are secured to swivel pins 304 mounted on the knife holders 210. For yieldingly holding the ironers in position to engage the welt during the cutting stroke of the knives the pins 304 have secured to their outer ends downwardly extending plates 306 (Fig. 15) which are mounted in recesses provided in the knife holders and are urged rearwardly by springs 308 mounted in extensions of said recesses. The springs 308 hold the plates 306 against vertical walls 310 of said recesses thereby locating the ironers in operative position.

For removing the waste ends of the welt from the knives 208 and for scraping off any foreign matter such as wax which may be picked up by the knives, the illustrated machine is provided with wiper members 312 (Fig. 10) which are constructed and arranged to move longitudinally of the upper surfaces of the knives after the cutting operation has been completed. The wiper members are herein illustrated as curved arms which are pivoted at their rear ends on brackets 314 secured to the knife holders. For operating the wipers 312 they are each provided with an arm 316 which extends outwardly from the rear portion of the wiper. During the rearward movement of the knife assembly after the cutting operation has been completed the arms 316 engage lugs 318 extending downwardly from the plates 262, causing the wiping members to swing toward each other to perform the wiping operation. During the forward or return movement of the knives, torsion springs 320 return the wipers to their respective initial positions unless the knives have become coated with wax or other foreign matter which prevents free movement of the wipers. In this event the wipers are positively returned by lugs 322 (Fig. 13) extending downwardly from plates 262 secured to the forward portions of the brackets 220, said lugs being arranged to engage the arms 316 during the forward movement of

the knives if the springs 320 have failed to operate.

The crease finders 38 which support the welt for the butting operation are similar in construction to the crease finders illustrated and described in United States Letters Patent No. 1,584,061, granted April 21, 1925, upon an application filed in the name of Edward Erickson. The crease finders support the welt in such positions that the 5 welt ends are beveled or skived off both lengthwise and transversely outward, the paths of the cutting knives through the end portions of the welt being such that the inseam stitches are not cut and the ends of the welt are squarely cut 10 off, providing terminal edges which are parallel to the heel-breast line of the shoe. Like mechanisms are provided for supporting and operating the crease finders and the following description is applicable to either one. Referring to Fig. 16, 15 the illustrated crease finder has a shank 326 which is secured to a dovetail slide 328 which is mounted in a groove in a head 330 for movement generally widthwise of the shoe. The head 330 is removably mounted on a bracket 332 at the forward end of a slide 454 mounted in an arm 452 which is journaled upon a shaft 334 secured to an extension of the machine head. The head 330 is located on the bracket 332 by a pin 338 (Fig. 21) which extends through a vertical hole in the forward portion of the swinging bracket 332 and has a cross-head 336 which is T-shaped in cross-section and fits freely into a T-shaped groove 340 provided in the base of the head 330 and extends into a groove 344 in the bracket 332. The head 330 is positioned on the bracket 332 by bringing its rear face into engagement with an abutment 342 on the bracket and is secured to the bracket by a clamping nut 344 (Fig. 1) which is threaded upon the lower end of the pin 338 and engages the bottom surface of the bracket 332. For simultaneously operating both slides 328 to move the crease finders widthwise of the shoe to and from welt supporting position a cam 346 (Fig. 19) is keyed to the cam shaft 134. The cam 346 operates an arm 348 which is secured to a rock-shaft 350 (Fig. 17) which is journaled in the machine head. The rockshaft 350 has secured thereto two gear segments 352 which mesh with beveled gears 354 at the rear ends of rockshafts 356 which are mounted in journals 358 secured in the machine head. Referring now to Fig. 18, the rockshaft 356 therein illustrated has a universal connection to a sleeve 360 which is fluted for the reception of a shaft 362 the rear portion of which is provided with teeth 364 which slide in the sleeve 360 and provide a connection whereby rotation of the sleeve is imparted to the shaft. The forward end of the shaft 362 has a universal connection to a rockshaft 366 in the bracket 332. The illustrated connections from the rockshaft 356 to the rockshaft 366 permit the crease finder assembly to swing toward and from the shoe and permit adjustment thereof lengthwise of the shoe. Referring now to Fig. 16, the rockshaft 366 is journaled in extensions 372 of the bracket 332 and has secured thereto a lever 374 the upper end of which has a head 376 in which is journaled a cross pin 378 one end of which has secured thereto a block 380 and the opposite end of which has secured thereto a short lever 382 the outer end of which is connected by a link 384 to one of the extensions 372. The block 380 is slidably mounted in a vertical groove in a slide 388 (Fig. 20) which is mounted in the head 330 for movement in the same direction as the crease finder. The link 384 holds the block 380 in position to enter the groove 386 when the crease finder head is removed from the machine. Referring now to Fig. 21, the slide 388 is positioned between an inner wall of the head 330 and a downward extension 394 of the slide 328 on which the crease finder is mounted. For connecting the slide 388 to the downward extension 394 a locking ball 396 is mounted in a hole provided in said downward extension. The diameter of the ball is greater than the width of the extension 394, the portion of the ball projecting from the extension 394 being positioned alternately in a socket provided in the slide 388 and in a similar socket provided in a plate 398 which is secured to the head 330. During the inward movement of the crease finder to position it for the welt butting operation the ball 396 is seated in the recess in the slide 388 and connects said slide to the downward extension 394 of the crease finder slide. After the crease finder comes to the limit of its inward movement a stop block 400 secured to the outer end of said downward extension engages the end of the fixed plate 398. This occurs when the ball 396 is in alignment with the socket in said fixed plate and, consequently, further movement of the slide 388 transfers the ball from the socket in said slide to the socket in the fixed plate. The advancement of the slide 388 continues until it comes into its position illustrated in Fig. 20 and locks the ball 396 in the socket in the fixed plate 398. The ball 396 is in its locking position illustrated in Fig. 20 as the crease finder brackets swing inwardly toward each other to advance the crease finders into the welt crease. The ball remains in locking position after the welt butting operation while the crease finder brackets are urged inwardly to force the welted margin in the region of the heel-breast line firmly into engagement with the last. It will be understood that the reactive force of the crease finder is taken by the ball 396, thereby preventing undue strain on the connections for moving the crease finder slide through the head 330. Prior to the pounding of the inseam and the driving of the tacks the crease finders are retracted to prevent the pounding action from being exerted against the crease finders with resulting disfigurement of the crease-finder-engaging surface of the welt. The crease finder is retracted by movement of the slide 388 to the left as seen in Fig. 20. During such movement of the slide a stop or upward extension 402 of the slide engages a wall 404 of a recess in the slide 328 on which the crease finder is mounted. This occurs when the socket in the slide 388 comes into alignment with the ball 396. As the movement of the slide 388 continues the ball is transferred from the socket in the fixed plate 398 into the socket in the slide and during the rest of the movement of the slide the crease finder moves with it. In shearing off the waste ends of the welt the welt butting knives operate in conjunction with two anvils 406 (Fig. 16) which are substantially the same in their construction and operation as the anvils illustrated and described in the patent to Erickson above referred to. The illustrated anvils are movable away from the shoe bottom to provide clearance for the tacking operation similarly to the anvils disclosed in the patent to Blanchard hereinbefore referred to. Referring to Fig. 16, the anvil 406 is secured to a slide 408 which is mounted in the head 330 for movement in the same direction as the crease finder. After the welt has been butted the slide 75

408 is moved to retract the anvil in order to provide clearance for the driving of the tacks which secure the welted margin of the upper to the insole. For operating the slide 408 and a like 5 slide which carries the other anvil, a cam block 410 (Fig. 23) is keyed to the shaft 134 and in the exposed side face of the cam block there is a cam path 412 in which there is mounted a roll 414 at the upper end of a cam lever 416 (Figs. 10 17 and 19) which is secured to a rockshaft 413 which is journaled in the machine head. Gear 15 segments 420 secured to the shaft 418 mesh with beveled gears 422 which are secured to rockshafts 424 mounted in journals 426 in opposite sides of the machine head. The gear segments 420 operate the anvils through two sets of connections one of which is illustrated in Fig. 18. Each rockshaft 424 has a universal connection to a sleeve 428 which is fluted for the reception of the 20 toothed end portion of a shaft 430 which has a universal connection to a rockshaft 432. Referring to Fig. 16, the rockshaft 432 is journaled in the extensions 372 of the bracket 332 and has secured thereto an arm 436 the upper end of 25 which has a head 438 in which is journaled a cross pin 440 to one end of which there is secured a block 442 which is slidably mounted in a groove provided in the slide 408. To the other end of the cross pin 440 there is secured a short lever 30 444 to the outer end of which is pivoted the upper end of a link 446 the lower end of which is pivoted to one of the extensions 372. The link 446 holds the block 442 in position to enter the groove in the slide 408 when the head 338 is removed 35 from the machine. To prevent the removal of the slide 408 from the head 338 when the head is removed from the machine a stop screw 448 (Fig. 20) is mounted in the rear wall of the head and has its end portion positioned in a 40 groove provided in the slide 408. To facilitate the assembly of the head 338 in the machine the screw 448 is so arranged that when the slide 408 is brought into engagement with it as illustrated in Fig. 20, said slide is positioned to receive the block 442. To further facilitate the assembly of the head 338 on the machine the slide 338 (Fig. 21) is provided with a socket which receives a spring pressed latch pin 450 which locates said 45 slide for reception of the block 442.

50 To afford adjustment of the head 338 lengthwise of the shoe the slide 454 is mounted in the swinging arm 452 for movement endwise thereof. As illustrated in Fig. 16, the arm 452 is provided with upper and lower channels within which the 55 slide 454 is mounted. For adjusting the slide 454 in the arm 452 a stud 456 is mounted in the arm 452 and arranged to extend outwardly from said arm through a slot 458 in the slide 454. Mounted on the stud 456 is a sleeve 460 having an eccentric head 462 on which there is freely 60 mounted a block 464 which is slidably mounted between vertical ribs in the slide 454 one of which is illustrated at 466. For holding the block 464 against the slide 454 the head 462 is provided 65 with a flange 468. The sleeve 460 extends outwardly from the slide 454 and is journaled in a bracket 470 (Fig. 2) extending downwardly from the arm 452 and is provided with a handle 472 to facilitate its operation. A clamping member 471 (Fig. 1) threaded upon the outer end of the stud 456 locks the sleeve 460 in adjusted position.

The arms 452 which carry the crease finders are individually adjustable up and down to position the anvils and the crease finders in operating 70 relation to the knives. The mechanism for so

adjusting the arm at the left of the machine is illustrated in Fig. 18. The vertical shaft 334 extends through bearings 478 and 480 in the arm which is positioned on the shaft 334 between a flange 492 in the lower portion of the shaft and a nut 484 secured to the reduced upper portion of the shaft. The threaded lower portion of the shaft extends freely through a block 486 secured to the machine head and nuts 488 and 490 are threaded upon the shaft and arranged to engage 10 respectively the upper and lower surfaces of the block. It will be seen that by turning the nuts 488 and 490 the shaft 334, together with the arm 452, may be vertically adjusted and secured in adjusted position. 15

In the illustrated machine as in the machine of the Erickson patent above referred to, the crease finders and the anvils are yieldingly swung toward the shoe in the machine to press the crease finders into the welt crease, thereby to 20 position them in correct relation to the welt for the welt butting operation. After the welt has been butted, the crease finders herein illustrated are again moved toward each other, this time under heavy pressure, to force the welted margin at opposite sides of the breast-line portion of the firmly against the last for the tacking operation hereinafter described. During the final 25 inward movement of the crease finders, tack driver guides hereinafter described are pressed against the sole-attaching face of the welt directly above the crease finders and grip the welt against the crease finders. The crease finders and the tack driver guides swing inwardly together after they have gripped the welt between them and undue 30 pressure of the crease finders against the welt seam is thus obviated. The inward movement of the tack driver guides is effected by simultaneously swinging the tacker heads by means of mechanism now to be described. The same 35 mechanism imparts both the preliminary and the final inward movements to the crease finders through connections from the tacker heads to the crease finder brackets, illustrated in Fig. 18, comprising a tongue 491 extending upwardly from 40 each crease finder bracket into a groove in the tacker head. Referring to Figs. 23 and 24, the mechanism for swinging the tacker heads and the crease finder brackets comprises a lever 492 which is keyed to a vertical shaft 494 and has 45 at its rear end a roll 496 which travels in a peripheral cam path 498 in the cam block 410. Two segments 502 (Figs. 24 and 26) are freely mounted on the hub of an arm 500 freely mounted on the shaft 494 below the lever 492 and have 50 secured between them an arm 500. A lever 502 is freely mounted on the shaft 494 below the arm 500 and is connected to the tacker head at the left of the machine by a link 504 (Fig. 23). The arm 500 and the lever 502 are connected together 55 at their outer ends by a right-and-left threaded screw 506 which is operable to adjust the tacker heads toward and from each other to position the anvils and crease finders to operate on shoes of different widths. For swinging the tacker head 60 at the right of the machine a lever 508 is mounted on a fixed vertical shaft 510 and the inner ends of the levers 502 and 508 are geared together at a point midway between the shaft 510 and the shaft 494. The lever 508 is connected to the 65 tacker head at the right of the machine by a link 512. When the machine is at rest, the arm 500 is held in its position illustrated in Fig. 23 by means hereinafter described and, consequently, the operation of the screw 506 moves the 70 75

lever 502 relatively to the arm 500 and adjusts the tacker heads toward or from each other. A set screw 514 secures the screw 506 in adjusted position and a plate 516 pivoted to the end of the lever 502 and having a pin-and-slot connection to the end of the arm 500 limits the adjustive movement of the lever 502 and prevents the tacker heads being positioned close enough together so that they would collide were the machine operated without a shoe in it. The cam lever 492 actuates the arm 500 to swing the tacker heads, the connections from the cam lever to said arm comprising an outward extension 518 of the cam lever, a swinging rod 520 pivoted to the arm 500, and a compression spring 522 mounted on the rod 520 and confined between a washer 524 providing an abutment at the free end of the rod and a block 526 slidably mounted on the rod and arranged to engage the extension 518 of the cam lever. The block 526 is positioned between the extension 518 of the cam lever and a bracket 528 on said extension arranged to overlie the block, and the block is provided with trunnions 530 which are seated in grooves provided in the extension 518 and bracket 528 by the spring 522. When the machine is at rest, the arm 500 is held against the extension 518 of the cam lever by the spring 522. During the first part of its operative movement, the cam lever 492 swings in a counterclockwise direction as seen in Fig. 23 and operates against the spring 522, swinging the arm 500 and the arm 502 to cause the crease finders to be pressed into the welt crease. As the movement of the crease finders is resisted by the shoe, further movement of the cam lever 492 compresses the spring 522 without further advancing the arms 500 and 502. As the cam lever nears the end of its operative movement, it operates the arm 532 to impart heavy pressure to the tacker heads and the crease finder brackets, thereby to force the welted margin of the shoe in the machine inwardly against the last to position it for the tacking operation hereinafter described. For operating the arm 532 the extension 518 of the cam lever has mounted in its cylindrical end portion 534 a headed pin 536 which is seated in a counterbore in the end portion of the lever and projects through a bore in the front face of the lever. The pin 536 is yieldingly held in its position illustrated in Fig. 23 by a heavy spring 538 which engages a flange in the head of the pin and is backed up by a hollow plug 540 which is threaded into the end portion 534 of the lever and is adjustable to vary the compression of the spring 538. During the initial operation of the cam lever 492 the pin 536 advances from its position in Fig. 23 into engagement with the arm 532. During this initial movement of the cam lever the crease finders are yieldingly advanced into the welt crease by the mechanism above described and the waste ends of the welt are cut off. During the further operation of the cam lever 492 after the pin 536 engages the arm 532, said arm is swung in a counterclockwise direction as seen in Fig. 23 to force the crease finders inwardly under the heavy pressure of the spring 538 through connections comprising the segments 542 and pawls 548 (Fig. 26) which engage ratchet teeth 546 provided in the segments. The pawls 548 are pivotally mounted on the arm 532 (Fig. 25) and are urged toward the segments by spring-pressed pins 572 in the headed end 552 of said arm 532. The pawls are positioned respectively above and below the arm 532 and are confined between the arm and flanges 550 extending from its headed end. When the pawls 548 are brought into engagement with the ratchet teeth in the segments 542 the arm 532 is operatively connected to the lever 502 which operates the tacker heads and the crease finder brackets. The extent of movement of the tacker heads and crease finder brackets by the arm 532 may be varied by adjusting said arm toward or from the headed pin 536. For so adjusting said arm an arm 554 (Fig. 23) is mounted on a fixed pivot 556 and has a pin-and-slot connection to an upward extension 558 (Fig. 25) of the head 552 of the arm 532. The arm 554 has a lengthwise bore in which there is mounted a spring-pressed sliding pin 560 which engages the pin 562 and urges the arm 532 in a clockwise direction as seen in Fig. 23. The outer portion of the bore in the arm 554 is threaded for the reception of a headed screw 564 the end of which engages the pin 562 and by its adjustment determines the distance between the arm 532 and the pin 536 when the machine is at rest. In order that the pawls 548 will not interfere with the adjustment of the arm 532 they are held out of engagement with the ratchet teeth 546 when the machine is at rest by a pin 566 in a forward extension 568 of the cam lever 492 which pin engages extensions 570 of the pawls. During the initial movement of the cam lever 492 the pin 566 passes off the extensions 570 of the pawls whereupon the pawls are swung into engagement with the ratchet teeth by the spring-pressed pins 572 (Fig. 25). In operating on some types of work such, for example, as women's shoes having thin welts, a heavy pressure of the crease finders against the welt would merely buckle the welt and fail to accomplish its purpose and should, therefore, be eliminated and, accordingly, the range of adjustive movement of the arm 532 by the screw 564 is sufficient to permit said arm to be swung in a counterclockwise direction, as seen in Fig. 23, into a position in which it will not be engaged by the pin 536 during the operation of the cam lever 492. If the machine is operated without a shoe in it a stop 573 on the machine head arrests the advancement of the segments 542.

After the final inward movement of the crease finders has been completed the crease finders are retracted by mechanism hereinbefore described, and the tack driver guides hold the welted margin of the upper in the position into which it has been brought by the combined inward movement of the tack driver guides and the crease finders. It will be understood that the crease finders could not be retracted while the tack driver guides remain in position to hold the welt unless some means were provided for preventing further inward movement of the tacker heads by the spring 522 (Fig. 23) as the crease finders are retracted. Accordingly, the illustrated machine is provided with a Horton clutch mechanism which operates to prevent further inward movement of the tacker heads and the crease finder brackets after the advancement of the crease finders by the cam lever 492 has been completed. The illustrated Horton clutch mechanism is mounted on a vertical shaft 574 (Figs. 30 and 31) secured in a bracket 576 on the machine head. Freely mounted on the shaft 574 and positioned between the bottom of the bracket 576 and the headed lower end of the shaft is a gear 578, which as illustrated in Figs. 23 and 30, meshes with a segment 580 formed in the lever 502. The gear 578 is counterbored, as illus-

trated in Fig. 31, for the reception of a ring 582 which is freely mounted on the headed lower end of the shaft 574 and supported on a plate 584 secured to said head. The ring 582 is provided with radial notches (Fig. 23) which are uniformly spaced apart and contain rolls 586 the diameters of which are somewhat greater than the thickness of the ring. The rolls 586 are positioned between the inner wall of the gear 578 and flat surfaces 588 provided in the head of the shaft 574. When the ring 582 is in its position illustrated in Fig. 23 with the rolls 586 located opposite the centers of the flat surfaces 588 said rolls are freely mounted in their enclosures and the gear 578 is free to turn upon the ring 582. The ring 582 remains in this position during the operation of the cam lever 492 which swings the tacker heads and the crease finder brackets. After the advancement of the tacker heads and the crease finder brackets has been completed the ring 582 is turned in a clockwise direction, as seen in Fig. 23, to bring the rolls 586 into position to lock the gear 578 against clockwise movement thereby to prevent further advancement of the tacker heads. For turning the ring 582 a lever 590 (Fig. 30) is secured to a shaft 592 which is journaled in the bracket 576 and said lever is pivoted at its lower end to a link 594 which, in turn, is pivoted to an extension 596 (Figs. 23 and 31) of the ring 582. The lever 590 is operated by the expansion of a spring 598 which is mounted in a bore in the bracket 576 and operates a pin 600 which engages the upper end of the lever 590. The operation of the lever 590 is controlled and timed by a cam lever 602 (Fig. 23) which is secured to a shaft 604 which is journaled in the machine frame and coupled to the shaft 592. The lever 602 is operated by a cam 606 on the shaft 134. The ring 582 remains in locking position during the pounding and tacking operations and thereafter during the greater part of the outward swinging movement of the tacker heads and the crease finder brackets. It will be understood that such movement of the tacker heads by the operation of the cam lever 492 is not prevented by the Horton clutch mechanism since the gear 578 is free to move in a counterclockwise direction, as seen in Fig. 23, when the rolls 586 are in their locking position.

Referring to Figs. 1, 32 and 36, the illustrated mechanism for pounding the inseam and tacking the welted margin of the upper to the insole comprises four slides 608, two in each tacker head, which are operated by heavy springs 610 through levers 612 the outer ends of which are pivoted to the upper ends of rods 614 on which the springs are mounted. The springs are seated in hollow extensions 616 of plates 662 and 664 which carry the tack drivers and the levers 612 are pivoted to upward extensions 613 of said plates. For connecting the inner ends of the levers 612 to the slides 608 said levers are provided at their free ends with fixtures (Fig. 33) through which the heavy pressure of the springs 610 is imparted to the slides 608. Said fixtures are positioned in contiguous relation to each other on the upper end faces of the slides 608, as illustrated in Fig. 33, and are confined between extensions 734 of the slides 608 the inner side walls of which are provided with longitudinal grooves within which are mounted rolls 736 journaled on studs 738 extending outwardly from L-shaped members 740 secured to the levers 612. Each member 740 carries a shoe 742 which is U-shaped in cross-section

and is swiveled on a horizontal cylindrical portion 744 of the L-shaped member 740. The upwardly extending flanges of each shoe 742 are rounded and each of the levers 612 is provided with similarly rounded recesses to receive the flanges of the shoe and to provide abutment surfaces for the shoe whereby the operative movement of the lever is transmitted through the shoe to the slide 608. The springs 610 are energized or compressed for the pounding and tack driving operations by the operation of a cam 618 (Figs. 23 and 35) which actuates a lever 620 (Figs. 2 and 34) extending forwardly of the machine from said cam and pivoted midway between its ends on a fixed shaft 622. At its forward end the lever 620 has a central arm 624 and two arms 626 at opposite sides of and uniformly spaced from the arms 624. The central arm 624 is positioned between the shafts 222 on which the tacker heads swing and is provided with trunnions 630 which are positioned between flanges 632 and 634 (Fig. 32) formed in slides 636 on the shafts 222. Each of the arms 626 has a trunnion 638 which is positioned between the flanges 632 and 634. It will be seen that the construction and arrangement of the slides 636 and the cam lever 620 are such that the tacker heads are free to swing upon the shafts 628 without affecting the operative relation of the cam lever to said slides. The slides 636 operate like mechanism in the two tacker heads and it will be understood that the following description of the mechanism in the tacker head at the left of the machine illustrated in Figs. 32 and 36 is equally applicable to the corresponding mechanism in the other tacker head. Referring to Fig. 32, the illustrated slide 636 has an upper flange 640 between which and the central flange 632 are slidably mounted pivot blocks 642 (Figs. 34 and 36) on connected levers 646 and 648 (Fig. 36) secured to opposite ends of a horizontal shaft 650 journaled in a cylindrical portion 652 of the tacker head. The lever 648 has pivoted at its free end the upper end of a link 654 which is pivoted at its lower end to a slide 656 which is mounted in a T-way 658 in the tacker head for movement downwardly and laterally toward a vertical plane common to the longitudinal median line of a shoe in the machine. Mounted between the slide 656 and a plate 660 secured to forward extensions of the slide are the two plates 662 and 664 (Fig. 36) which carry the tack drivers, the former of which has a horizontal rearwardly extending tongue 666 which is slidably mounted in a groove in the slide 656 and a forwardly extending horizontal tongue 668 which is slidably mounted in a groove in the plate 664. The plates 662 and 664 carry the tack driving and inseam pounding members which are hereinafter described. For adjusting the plate 662 widthwise of the shoe to vary the position of the rear tacker an adjusting screw 670 is threaded into a socket in a forward extension of the slide 656 and is journaled in a bearing 672 (Fig. 32) which is an integral part of the plate 662. For effecting a like adjustment of the forward plate 664 an adjusting screw 674 is threaded into a lug 675 extending forwardly from the plate 660 and is journaled in a bearing in a lug 676 extending forwardly from the plate 664. Each of the plates 662 and 664 has mounted in a T-way in its inner side margin a slide 678 which, as illustrated in Fig. 36, is H-shaped in cross-section and, as illustrated in Fig. 32, is positioned parallel to the T-way 658 in which the slide 656 is mounted. The pounding of the inseam is effected by the down thrust of the slide 608 against the 75

slide 678 by the spring 610. The slides 678 have inwardly offset heads 680 at their lower ends, into which tacks are automatically fed through tubes 281 from a separator 283 (Fig. 2). The tacks are driven by pins 100 which are operated by the expansion of the springs 610. As seen in cross-section in Fig. 36 the slides 678 project from the plates 662 and 664 and provide bearings on which are slidably mounted the slides 608. The slides 10 678 have at their upper ends lugs 682 (Fig. 32) which are normally held against the plates 662 and 664, respectively, by springs 684 mounted in grooves in the plates and confined between end walls at the upper extremities of the grooves and 15 headed pins 686 mounted in the slides 678 and extending into said grooves. During the downward movement of the slide 656 the corrugated lower ends of the heads 680 engage the sole attaching face of the welt and as the downward movement of the slide 656 continues the springs 20 684 are compressed to increase the pressure of the heads 680 against the welt thereby to grip the welt between said heads and the crease finder. During the greater part of the downward movement 25 of the slide 656 the tack driving and pounding instrumentalities are held in the position illustrated in Fig. 32 by latch members 688 which engage the levers 612. For disengaging the latch members 688 from the levers to permit the springs 30 610 to operate, a lever 690 is pivotally mounted between upward extensions of the plate 660 and the slide 656 and has its rounded end positioned to engage short arms 692 extending laterally from the latch members 688. During the downward movement of the slide 656 the outer end of the lever 690 engages the upper end of a plate 694 which is adjustably secured to the tacker head and as the downward movement of the slide 656 continues thereafter the lever 690 is swung in a 35 clockwise direction, as seen in Fig. 32, thereby disengaging the latch member 688 from the lever 612 and permitting the springs 610 to move the slides 608 downwardly under heavy pressure to drive the tacks and to pound the inseam of the 40 shoe. For driving the tacks each of the slides 608 has a block 696 adjustably mounted in a suitable groove provided therein. As illustrated in Fig. 36 the blocks 696 are positioned together and the grooves in the slides 608 provide an 45 enclosure for the two blocks. Each block 696 is adjustably secured to its slide 608 by a clamping screw 698 (Fig. 32) which extends through a slot in the slide and is threaded into the block 696. Each of the blocks 696 has mounted therein and 50 extending downwardly therefrom a tack driving pin 700 and a key 702 (Fig. 36) is provided in each of the blocks 696 to secure the pins 700 thereto. The lower portions of the pins 700 are slidably mounted in longitudinal bores 708 (Fig. 55 32) in the heads 680 of the slides 678. For taking the force of the tack driving strokes of the pins 700 abutment screws 704 are threaded into bosses 706 on the slides 608 and engage the upper faces of the blocks 696. Referring now to Figs. 37 and 60 65 38, each of the bores 708 in the heads 680 communicates at its lower end with a tack pocket provided by fingers 710 which are mounted in a recess provided in the head 680 and held therein by a retainer plate 712. Each finger 710 has a 70 stud 714 which is mounted for rocking movement in the head 680 and carries a torsion spring 716 which urges the finger against a wall 718 formed in the head. To facilitate the removal of tacks which become jammed in the tack pocket each of the heads 680 is provided with an opening which,

as illustrated in Fig. 37, communicates with the finger 710 shown at the left in said figure, and a cover plate 722 is provided for said opening. The plate 722 has a dovetail tongue and groove connection to the head 680 and is yieldingly held in 5 position to cover the opening in the head by a spring-pressed ball 724 mounted in the head. When it is desired to extricate a fouled tack from the tack pocket the plate 722 is slid out of alignment with the opening in the head and the exposed finger 710 is swung into a horizontal position by turning the stud 714 to expose the tack and permit its removal. 10

The tack driving springs 610 (Fig. 32) are energized or compressed for the tacking and pounding operation by the upward movement of the slide 656. To this end the tacker head has secured thereto, as illustrated in Figs. 2 and 32, an arm 726 which has an L-shaped extension the end face of which engages rolls 728 mounted on extensions of crosspins 730 which connect the pins 614 to the levers 612. The arm 726 acts as an abutment to limit the upward movement of the pins 614 with the slide 656 and during the continued upward movement of said slides after the 25 rolls 728 engage the arm the springs 610 are compressed and the arms 612 are swung in a counterclockwise direction, as seen in Fig. 32, to bring them into the position illustrated in said figure, whereupon the latch members 688 are 30 swung into latching position by spring pressed pins 732 which engage the arms 692 of the latch members. After the latch members have swung into latching position the slide 656 moves downwardly slightly to cause the pressure of the springs 35 610 to be taken by the latch members and to relieve the pressure of the rolls 728 against the arms 726 thereby to permit horizontal adjustment of the plates 662 and 664.

The illustrated machine is provided with a back stop or plate 746 (Fig. 2) which is engaged by the heel end of the shoe as the shoe is positioned in the machine and is locked against rearward movement before the ends of the welt are butted in order to provide an abutment against which the knives may operate. In addition to the usual function of a back stop the illustrated stop also serves as an ejector to move the shoe out of the machine after the operations thereon have been completed and before the crease finders and the 40 anvils are returned to their initial positions thereby preventing engagement of the heel seat portion of the shoe with said members during its forward movement out of the machine. The back stop plate 746 is secured to the forward portion 45 of a horizontal slide 748 which is mounted in the machine head for longitudinal movement. The slide 748 is yieldingly held at the limit of its forward movement by a vertical lever 750 which is mounted on a shaft 752 and urged in a clockwise 50 direction, as seen in Fig. 2, by a spring 754 at its upper end. When the machine is at rest the back stop is at the limit of its forward movement, as illustrated in Fig. 2. As a shoe is introduced into the machine its heel end engages the back stop and moves it rearwardly. When the back stop is employed as a gage for positioning the shoe in the machine the rearward movement of the back stop by the shoe is arrested by the upper end of an arm 756 which is engaged by a shoulder 55 60 758 provided in the slide. The arm 756 is secured to a cross shaft 760 and may be adjusted to vary the stop position of the back stop by turning a shaft 762 which is journaled in the lower portion of the head and extends forwardly to the front 75

of the machine and has secured to its rear portion a spiral gear 764 which meshes with a spiral gear 766 on the cross shaft 760. The portion of the shaft 762 which extends forwardly from the machine frame has a beveled disk 824 (Fig. 3) freely mounted thereon and on the beveled surface of the disk characters indicating shoe sizes are inscribed. An indicator fixed on the head is arranged to register with said disk. Splined on the shaft 762 is a knob 826 which has a pin 828 which is arranged to be positioned in any one of a series of sockets 829 in the disk 824. For holding the knob against the disk, spring-pressed pins 830 are mounted in bores in the knob and arranged to engage an end plate 831 on the shaft 762. On the hub of the knob 826 there are inscribed characters indicating different styles or types of shoes said characters being arranged to register alternatively with a mark on the hub of the disk 824. It will be understood that the knob 826 is turned relatively to the disk 824 to adjust the knob in accordance with the style or type of shoe to be operated upon, while the knob and the disk are adjusted as a unit to position the stop 756 in accordance with the size of shoe to be operated upon. When there is no shoe in the machine the back gage 746 is yieldingly held at the limit of its forward movement by the spring 754. When a shoe is positioned in the machine the rear end of the shoe engages the back gage and moves it rearwardly until the shoe is arrested by the engagement of the ends of the inseam with the anvils or until the slide 748 which carries the back gage is arrested by the stop 756. For holding the back stop against rearward movement a pair of pawls 834 (Fig. 27) are brought into engagement with a ratchet plate 836 on the slide 748 by springs 838 (Fig. 29) arranged to engage lugs 848 extending downwardly from the pawls. After the operation on the shoe is completed and before the shoe is removed from the machine an arm 842 loose on the shaft 494 swings in a clockwise direction as seen in Fig. 27 to disengage the pawls from the ratchet plate. Thereafter a cam 844 (Fig. 18) operating against a roll 846 on the lever 750 moves the slide 748 forwardly to eject the shoe from the machine. Referring to Figs. 23 and 27 the shaft 494 on which is loosely mounted the arm 842 is turned in a counterclockwise direction by the operation of the cam lever 492 early in the machine cycle thereby swinging the arm 842 in a counterclockwise direction through connections now to be described and permitting the springs 838 to advance the pawls into ratchet-engaging position. Keyed to the lower portion of the shaft 494 is a plate 848 (Fig. 28) having a downwardly extending flange 850, and a ring 852 is positioned between the arm 842 and the plate 848 and is freely mounted on the hub of said arm. Mounted in a notch provided in the ring 852 is a roll 854 the diameter of which is somewhat greater than the thickness of said ring. The hub of the arm 842 has a flat surface 856 (Fig. 27) which provides one element of a Horton clutch mechanism, the roll 854 being positioned between said surface and the flange 850. The ring 852 and the arm 842 are provided respectively with extensions 858 and 860 which are positioned between stops 862 and 864 (Fig. 18) secured to the machine head. A spring-pressed pin 866 mounted in the extension 860 engages the extension 858 of the ring 852 and urges the ring in a clockwise direction as seen in Fig. 27 and wedges the roll 854 between the flat surface 856 on the hub of the arm 842 and the flange 850 of the plate 848. The springs 838 (Fig. 29) which advance the pawls 834 urge the arm 842 in a counterclockwise direction, as seen in Fig. 27, when the pawls are retracted, thus cooperating with the spring pressed pin 866 to hold the roll 854 in its wedged position. Early in the machine cycle the shaft 494 is swung in a counterclockwise direction as seen in Fig. 27 permitting the springs 838 (Fig. 29) to advance the pawls 834 into ratchet engaging position. After the pawls have engaged the ratchet plate the extension 860 of the arm 842 engages its stop 862 and during the continued counterclockwise movement of the shaft 494 thereafter the plate 848 turns about the hub of the arm 842. After the operations on the shoe have been completed the shaft 494 turns in a clockwise direction to swing the tacker heads and the crease finder brackets outwardly from the shoe. Such movement of the shaft 494 imparts clockwise movement to the plate 848 and through the Horton clutch mechanism above described the movement of the plate is imparted to the arm 842 thereby retracting the pawls 834 until the extension 858 of the ring 852 engages its stop 862 thereby momentarily releasing the roll 854 to permit the shaft 494 to complete its clockwise movement without interference from the Horton clutch. Immediately thereafter the springs which operate the pawls urge the arm 842 in a counter clockwise direction causing the roll to be wedged again between the hub of the arm and the flange of the plate 848 and restoring the parts to their initial position.

For operating the cam shaft 134 a power-driven worm shaft 768 (Fig. 39) is journaled in the machine head and has secured thereto a worm 770 which meshes with a worm gear 772 which is freely mounted on the cam shaft 134. For connecting the worm gear 772 to the cam shaft the illustrated machine is provided with a one-revolution clutch mechanism of known construction comprising a rotor 774 (Fig. 23) which is keyed to the cam shaft and has pivoted thereto a stop member 776 which is normally held against a shoulder 778 (Fig. 40) on the rotor 774 by a spring 780. The stop member 776 has a half-round extension 784 which is positioned adjacent to the inner edge face of a cam ring 782 secured to the worm gear 772. When the machine is at rest the stop member 776 is held in its position illustrated in Figs. 39 and 40 by a swinging arm 786 and the half-round extension 784 is so positioned that the cam ring 782 moves freely about said extension. When it is desired to start the machine the operator steps on a treadle 788 (Figs. 1 and 2) thereby moving downwardly a link 790 pivoted to the treadle and pivoted at its upper end to an arm 792 secured to a rock shaft 794 the operation of which moves downwardly a link 796 connecting an arm 798 on the shaft 794 and an arm 800 on a rock shaft 802. Fast on the rock shaft 802 is an upwardly extending arm 804 the upper end of which is pivoted to a block 806 (Fig. 39) fixed to a slide rod 808 which carries a vertically swinging bar 810 which engages a boss 812 on the arm 786, the boss being held against a shoulder in the bar 810 by a tension spring 816. It will be seen that the depression of the treadle 788 moves the bar 810 to the right, as seen in Fig. 39, disengaging the arm 786 from the stop member 776 and permitting the spring 780 (Fig. 40) to swing the stop member clockwise into engagement with the shoulder 778 on the rotor 774. The half-round extension of the member 776 is thus posi-

tioned to be engaged by the nearest projection 814 on the ring 782 thereby connecting the worm gear to the rotor 774 and moving it in a clockwise direction. During the movement of the rotor a cam 818 (Fig. 39) engages a roll 820 on the bar 810 and swings the bar downwardly against the pressure of a spring-pressed pin 822 carried by the slide 808 and arranged to hold the roll against the cam. The downward movement of the bar 810 disengages it from the arm 786 and permits the arm to return to its initial position for engagement with the stop member 776 after the rotor 774 has completed a single revolution. For preventing operation of the stop member 776 by the treadle a sliding pin 823 is mounted in the hub of the cam 818 and urged by a spring in said hub into position to engage an upward extension 825 of the stop member (Fig. 40).

For turning the machine over by hand, a hand wheel 868 (Fig. 9) is secured to a short shaft 870 which is journaled in a bearing in a bracket 872 on the machine head and has secured to its inner end a pinion 874. The shaft 870 is movable endwise thereof in its bearing to move the pinion to and from position to mesh with the gear teeth 876 formed in the cam 132 (Fig. 8) which operates the shoe supporting jack.

The operation of the illustrated machine is as follows:—A welted unsoled shoe on its last is mounted on the last pin on the jack post 36 (Fig. 1) and the jack post is swung inwardly to position the shoe lengthwise thereof relatively to the operating parts of the machine. During the inward movement of the jack the heel seat portion of the shoe engages the curved bottom edge of the plate 217 (Fig. 18) on the holdown 40 causing the shoe to be moved downwardly to position it vertically relatively to the operating parts. As the inward movement of the jack continues, the crease finders 38 engage the shoe in the welt crease thereby positioning it widthwise thereof relatively to the operating parts. The inward movement of the jack is arrested by the engagement of the ends of the inseam with the anvils or by the engagement of the back stop slide 748 (Fig. 2) with the stop 756. It will be understood that if the stop 756 is employed to gage the position of the shoe it is adjusted in accordance with the size and type of shoe to be operated upon and if it is not employed it is swung rearwardly into an inoperative position. After the shoe has been positioned the operator steps on the treadle 788 to start the machine. The sequence of the power operations of the machine is indicated by the cam chart (Fig. 47). During the first part of the machine cycle the tacker heads together with the crease finder brackets swing inwardly to press the crease finders into the welt crease (Fig. 42) and at the same time the back gage pawls 834 (Fig. 27) engage the ratchet plate 836 to lock the back gage in order to hold the shoe against rearward movement during the operation of the welt butting knives. During the latter part of the inward movement of the crease finders the knives move forwardly from their rest position indicated at a in Fig. 41 to their intermediate elevation indicated at b then vertically downward into their cutting elevation as indicated at c. By the time the knives have moved downwardly into their cutting elevation the back gage has been locked by the pawls 834 and the crease finders have been pressed inwardly into the welt crease to support the welt for the butting operation. The cutting stroke of the knives begins immediately

after they are brought down into the cutting elevation and in the course of the cutting stroke the knives advance from the position indicated at c into the position indicated at d. During the continued movement of the knives thereafter they travel upwardly and rearwardly to their position indicated at e then rearwardly in a horizontal path to the full line position of the knives in Fig. 41. The knives remain in this position until after the tacking and pounding operations have been completed and the tackers have been retracted and thereafter they move forwardly to their initial position. After the welt has been butted, the anvils are moved outwardly away from the shoe bottom to provide clearance for the tacking and pounding operation and at the same time the slides 656 (Fig. 32) which carry the tacking and pounding units are moved downwardly to bring the heads 680 of the slides 678 into engagement with the shoe bottom. Referring to Fig. 46 the forward heads 680 engage the sole attaching face of the welt and the inseam substance while the rear heads 682 engage the heel seat adjacent to the butted ends of the welt. It will be understood that the position of the tacks lengthwise of the shoe relatively to the welt ends may be varied by adjusting the slides 454 (Fig. 16) which carry the anvils. The forward heads 680 grip the welt against the crease finders, the springs 684 (Fig. 32) being compressed by the downward movement of the slides 656, to impart gripping pressure to the slides 678. After the heads 680 have been pressed against the welt, the downward movement of the slides 656 is interrupted to permit the crease finders and the tacker heads 35 to swing inwardly under heavy pressure to press the welted margin of the upper inwardly against the last and to bend the inseam substance inwardly as illustrated in Fig. 43. During the downward movement of the tacker slides 656, the shoe supporting jack is pressed upwardly and locked to hold the shoe against downward movement during the tacking and pounding operation. As soon as the final inward movement of the tacker heads and crease finder brackets has been completed the Horton clutch, illustrated in Fig. 23, is operated to lock said heads and brackets against further inward movement whereupon the crease finders are moved outwardly from the shoe into their position illustrated in Fig. 44 whereupon 50 the tacks are driven and the inseam substance is pounded thereby bending it over and pressing it downwardly as illustrated in Fig. 45. The jack is then moved downwardly and the tacker slides 656 are lifted to permit the shoe to be removed 55 from the machine whereupon the back gage is moved forwardly to eject the shoe. Thereafter the anvils and the crease finders are moved inwardly to their initial positions and at the same time the knives are moved forwardly to their initial positions and the Horton clutch which locks the tacker brackets is restored to its inoperative position.

It will be understood that if the work support illustrated in Fig. 6 is employed, the jack is 65 locked to prevent swinging movement thereof and the shoe is initially supported in the machine on the crease finders. The power operation of the jack remains the same as above described.

Having thus described my invention, what I claim as new and desire to secure by Letters Patent of the United States is:

1. In a welt-butting machine, a knife constructed and arranged for movement lengthwise 75

- of a welted shoe to butt one end of the welt, said knife, when the machine is at rest, being positioned away from the shoe bottom and opposite the breast line portion of the shoe, and means 5 for moving the knife from its rest position toward the toe end of the shoe and toward the shoe bottom to its cutting position.
2. In a welt-butting machine, a knife for butting one end of the welt of a welted shoe, means 10 for moving the knife toward the toe end of the shoe in a downwardly inclined path to an intermediate position, and means for moving the knife downwardly in a perpendicular path from its intermediate position to its cutting elevation.
- 15 3. In a welt-butting machine, a knife for butting one end of the welt of a welted shoe, a crease finder for supporting said end of the welt for the butting operation, a holder for the knife, a carrier for the holder, and an actuator for moving 20 the carrier first toward the toe end of the shoe and thereafter in the opposite direction to effect the cutting stroke of the knife.
4. In a welt-butting machine, a knife for butting one end of the welt of a welted shoe, a holder 25 for the knife, a carrier for the holder, an actuator for moving the carrier first toward the toe end of the shoe to position the knife for the beginning of its cutting stroke, then rearwardly to effect the cutting stroke, and means operating on the knife 30 holder during the movement of the carrier toward the toe end of the shoe to move the knife toward the shoe bottom.
- 35 5. In a welt-butting machine, a knife for butting one end of the welt of a welted shoe, a rocker on which the knife is mounted, a carrier for the rocker, an actuator for moving the carrier first forwardly toward the toe of the shoe to position the knife for the beginning of its cutting stroke, then rearwardly to effect the cutting stroke, and 40 means for actuating the rocker to transfer the knife from an elevated position to its cutting plane.
- 45 6. In a welt-butting machine, a knife for butting one end of the welt of a welted shoe, a rocker on which the knife is mounted, a carrier for the rocker, a rocker actuator carried by the carrier, means for effecting relative movement of the actuator and the carrier before the cutting stroke commences to transfer the knife from an elevated 50 position to its cutting plane as the carrier moves toward the toe of the shoe to position the knife for the beginning of its cutting stroke, and means for effecting relative movement of the carrier and the actuator after the cutting stroke has been 55 completed thereby to move the knife upwardly.
- 60 7. In a welt-butting machine, a knife for butting one end of the welt of a welted shoe, a rocker for moving the knife heightwise of the shoe, an actuator for rocking the rocker, a carrier for the 65 rocker and the actuator, means for operating the rocker during movement of the carrier toward the toe of the shoe thereby to move the knife downwardly from an elevated position to an intermediate elevation above its cutting plane, means for operating the actuator while the carrier remains at rest at the limit of its forward movement thereby to transfer the knife from its intermediate elevation to its cutting plane, and means for operating the actuator after the cutting 70 stroke has been completed thereby to move the knife upwardly.
- 75 8. In a welt-butting machine, a knife for butting one end of the welt of a welted shoe, a rocker for moving the knife heightwise of the shoe, means for moving the knife lengthwise of the shoe, and an actuator for operating the rocker before the cutting stroke of the knife to move the knife heightwise of the shoe into its operating plane and for operating the rocker after the cutting stroke of the knife and during further movement of the knife in the direction of its cutting stroke to move the knife away from the shoe bottom. 5
9. In a welt-butting machine, a knife for butting one end of the welt of a welted shoe, a rocker for moving the knife heightwise of the supported shoe, a slide for moving the knife lengthwise of the shoe, an actuator for the rocker carried by the slide, means for effecting relative movement of the slide and the actuator to cause the rocker 10 to move the knife heightwise of the shoe from a remote position into a cutting plane before the cutting operation commences, means for advancing the slide to operate the knife, and means for effecting relative movement of the slide and 15 the actuator after the cutting operation has been completed thereby to move the knife away from the shoe bottom.
10. In a welt-butting machine, a knife for butting one end of the welt of a welted shoe, a member for moving the knife heightwise of the supported shoe, a slide for moving the knife lengthwise of the shoe, a cam for operating said member which cam is carried by the slide, means for moving the slide forwardly toward the toe end 20 of the shoe, means for effecting relative movement of the cam and the slide during the forward movement of the slide thereby to move the knife from a remote position toward the shoe bottom, and means for operating the cam member 25 after the slide has come to rest at the limit of its forward movement for operating the cam to move the knife heightwise of the shoe into its cutting plane. 30
11. In a welt-butting machine, a knife for butting one end of the welt of a welted shoe, a rocker on which the knife is mounted, a slide to which the rocker is pivoted, a rocker actuating cam mounted on the slide and arranged for operative movement relatively to the slide, an actuator for 35 moving the slide forwardly toward the toe end of the shoe to position the knife for the beginning of its cutting stroke, then rearwardly of the shoe to effect the cutting stroke, then forwardly again to the starting position, means for effecting relative movement of the cam and the slide during the initial forward movement of the slide thereby to move the knife from a remote position toward the shoe bottom, and means for effecting relative movement of the slide and the cam during 40 the rearward movement of the slide after the cutting stroke has been completed thereby to move the knife away from the shoe bottom. 45
12. In a welt-butting machine, two knives for simultaneously butting the ends of the welt of a 50 welted shoe, two slides for operating the knives, two swinging brackets in which the slides are respectively mounted, an actuator for moving the slides forwardly toward the toe of the shoe to position the knives at the beginning of their cutting stroke, then rearwardly to effect the cutting stroke, then forwardly to return the knives to their initial positions, and connections from the actuator to said slides constructed and arranged to permit swinging movement of the 55 slides. 60
13. In a welt-butting machine, two knives for simultaneously butting the ends of the welt of a 65 welted shoe, two slides for operating the knives, two swinging brackets in which the slides are re- 70

- 5 spectively mounted, an actuator for moving the slides forwardly toward the toe of the shoe to position the knives at the beginning of their cutting stroke, then rearwardly to effect the cutting stroke, then forwardly to return the knives to their initial positions, members carried by the slides for moving the knives heightwise of the shoe to and from their cutting plane, an actuator for said members, and connections from the last-mentioned actuator for operating said members constructed and arranged to permit swinging movement of said brackets.
- 10 14. In a machine for operating on welted shoes, a crease finder, a head in which the crease finder is slidably mounted for operative movement withwise of a shoe in the machine relatively to the head, a support on which the head is mounted, and connections from the head to the support constructed and arranged to permit removal of the head of the machine.
- 15 15. In a machine for operating on welted shoes, a crease finder, a carrier in which the crease finder is slidably mounted for operative movement widthwise of a shoe in the machine, means for moving the carrier widthwise of the shoe, and means for moving the crease finder widthwise of the shoe in the carrier.
- 20 16. In a machine for operating on welted shoes, a crease finder, a carrier therefor, means for moving the carrier widthwise of a shoe in the machine to advance the crease finder into the welt crease, and means for thereafter moving the crease finder relatively to the carrier to withdraw it from the welt crease.
- 25 17. In a machine for operating on welted shoes, a crease finder, a head in which the crease finder is mounted for movement widthwise of a shoe in the machine, an actuator for moving the crease finder in the head, and connections from the actuator to the crease finder constructed and arranged to permit removal of the head from the machine.
- 30 18. In a machine for operating on welted shoes, a crease finder, a head in which the crease finder is mounted for movement widthwise of a shoe in the machine, an actuator for moving the crease finder in the head, connections from the actuator to the crease finder constructed and arranged to permit removal of the head from the machine, said connections including a pivot member on the actuator, and means for maintaining the operative relation of the pivot member to the crease finder when the head is out of the machine.
- 35 19. In a machine for operating on welted shoes, a crease finder, a slide on which the crease finder is mounted, a carrier for the slide movable widthwise of a shoe in the machine, means for adjusting the slide relatively to the carrier lengthwise of the shoe, an actuator, and connections from the actuator to the crease finder for moving the crease finder in the slide widthwise of the shoe, said connections being constructed and arranged to permit movement of the carrier both lengthwise and widthwise of the shoe.
- 40 20. In a welt-butting machine, a welt-butting knife, an anvil against which the knife operates to shear off the welt, and means for adjusting the anvil heightwise of a shoe in the machine relatively to the knife.
- 45 21. In a welt-butting machine, a welt-butting knife, a crease finder for supporting the welt of a shoe in the machine, an anvil against which the knife operates to shear off the welt, a car-
- 50 rier for the crease finder and the anvil, said carrier being adjustable heightwise of a shoe in the machine to adjust the anvil relatively to the knife.
- 55 22. In a welt-butting machine, a welt-butting knife, a crease finder for supporting the welt during the butting operation, an anvil against which the knife operates to shear off the welt, a carrier for the crease finder and the anvil, said carrier being adjustable heightwise of a shoe in the machine to adjust the anvil relatively to the knife, a head in which the knife is mounted, means for moving the head widthwise of the shoe, and connections between the head and the carrier for imparting such widthwise movement of the head to the carrier, said connections being constructed and arranged to permit adjustment of the carrier heightwise of the shoe relatively to the head.
- 60 23. In a welt-butting machine, a welt-butting knife, a shear member against which the knife operates to shear off the welt, a head in which the shear member is mounted for movement to and from shearing position, a carrier for the head, connections for securing the head to the carrier constructed and arranged to permit removal of the head from the machine, and means for adjusting the carrier both lengthwise and heightwise of a shoe in the machine.
- 65 24. In a welt-butting machine, a welt-butting knife, a shear member therefor, a crease finder for supporting the welt of a shoe in the machine during the welt-butting operation, and a carrier in which both the shear member and the crease finder are mounted for operative movement widthwise of the shoe relatively to the carrier.
- 70 25. In a welt-butting machine, a welt-butting knife, a shear member against which the knife operates, a crease finder for supporting the welt of a shoe in the machine during the welt-butting operation, a carrier in which both the shear member and the crease finder are mounted for movement widthwise of the shoe relatively to the carrier, means for moving the carrier widthwise of the shoe, means for adjusting the carrier lengthwise of the shoe, an actuator for moving the crease finder relatively to the carrier widthwise of the shoe, another actuator for moving the shear member relatively to the carrier widthwise of the shoe, and operating means from said actuators to the crease finder and shear member respectively constructed and arranged to permit movement of the carrier both lengthwise and widthwise of the shoe.
- 75 26. In a shoe machine, means for inserting fastenings to secure the overlasted margin of a welted shoe to an insole, a carrier for the fastening inserting means, a member through which fastenings are driven, and means operating longitudinally of said member to press said member toward the shoe bottom with a component of movement widthwise of the shoe against its welted margin thereby to turn the end portions of the inseam inwardly toward the center of the shoe bottom.
- 80 27. In a welt-butting machine, welt-butting knives and grippers constructed and arranged to grip between them a substantial extent of the width of the end portions of the welt of a welted shoe in the machine after they have been butted to advance together thereby to urge the welted margins of the upper toward each other.
- 85 28. In a welt-butting machine, welt-butting knives, crease finders constructed and arranged to support the end portions of the welt of a

- welted shoe in the machine, gripper members constructed and arranged for movement heightwise of the shoe to grip the end portions of the welt against the crease finders after the welt has been butted, and means for advancing the crease finders and the gripper members together toward the middle of the shoe.
29. In a welt-butting machine, welt-butting knives, crease finders, and grippers constructed and arranged to grip the end portions of the welt of a welted shoe in the machine against the crease finders after the welt has been butted, means for advancing the grippers together toward the middle of the shoe thereby to press the upper against a last therein, and means for thereafter retracting the crease finders while the pressure of the grippers against the welt is maintained to hold the welted margin in the position to which the crease finders and grippers have brought it.
30. In a welt-butting machine, welt-butting knives, crease finders constructed and arranged to support the end portions of the welt of a welted shoe in the machine, fastening inserting devices for securing that portion of the upper in the region of the heel breast line to the insole, said fastening inserting devices including members constructed and arranged to move heightwise of the shoe to grip the end portions of the welt against the crease finders after the welt has been butted, and means for advancing the crease finders and said members together toward the middle of the shoe thereby to press the welted margin of the upper against the last.
31. In a welt-butting machine, the combination with welt butting knives and crease finders of welt pounding means including welt engaging members constructed and arranged to grip the sole attaching face of the welt, means for pressing the welt engaging members against the welt after the welt has been butted thereby to grip the welt between said members and crease finders, and means for thereafter urging the welt engaging members and the crease finders toward the middle of the shoe thereby to force the welted margin of the upper firmly against the last.
32. In a welt-butting machine, the combination with welt-butting knives and crease finders of welt pounding means including welt engaging members provided with gripping surfaces constructed and arranged to engage the sole attaching face of the welt of a welted shoe in the machine, means for pressing the welt engaging members against the welt, means for thereafter retracting the crease finders while said members hold the welt against movement with the crease finders by pressure which is exerted against the last bottom, and means operated after the crease finders have been retracted to pound the welted margin of the upper against the welt.
33. In a welt-butting machine, crease finders, carriers therefor movable widthwise of a shoe in the machine, means for moving the carriers toward the shoe, such movement of the carriers being arrested by engagement of the crease finders within the welt crease, means for moving the crease finders in their carriers to retract the crease finders from the welt crease, and means for holding the carriers against movement toward the shoe during the retraction of the crease finders.
34. In a welt-butting machine, crease finders, carriers therefor movable widthwise of a shoe in the machine, means for moving the carriers toward the shoe, such movement of the carriers
- being arrested by engagement of the crease finders within the welt crease, means for moving the crease finders in their carriers to retract the crease finders from the welt crease, mechanism for holding the carriers against movement toward the shoe during the retraction of the crease finders, means for fastening the welted margin of the upper to the insole including welt engaging members through which fastenings are driven, and means for pressing said members against the sole attaching face of the welt during the retraction of the crease finders thereby to hold the welted margin against movement with the crease finders.
35. In a welt-butting machine, pounders constructed and arranged to engage the inner margin only of the welt and the upper portion of the inseam substance and to operate in inclined paths extending heightwise of a shoe in the machine and inwardly toward the middle of the shoe.
36. In a welt-butting machine, the combination with welt-butting cutters, of means constructed and arranged to operate against the inseam substance of a shoe in the machine to bend the inseam substance inwardly toward the middle of the shoe and to pound it against the insole.
37. In a welt-butting machine, means for tacking the butted ends of the welt of a welted shoe in the machine to the insole, said tacking means including tack-driver guides, means for exerting heavy pressure against said guides to press down the inseam in the region of the welt butts and a support for holding the shoe against the force applied to the tack-driver guides.
38. In a welt-butting machine, means for tacking the butted ends of the welt of a welted shoe in the machine to the insole, said tacking means comprising tack-driver guides which are supported by the welt during the tack-driving operation, and tack drivers the tack-driving movement of which is arrested by the engagement of the drivers with the guides.
39. In a welt-butting machine, means for tacking the butted ends of the welt of a welted shoe in the machine to the insole, said tacking means being constructed and arranged to operate in inclined paths extending toward the shoe bottom and inwardly toward the middle of the shoe, said tacking means comprising tack-driver guides which are supported by the welt during the tack-driving operation, and tack drivers the tack-driving movement of which is arrested by the engagement of the drivers with the guides thereby to cause the guides to bend the inseam substance toward the middle of the shoe and to press it toward the plane of the insole.
40. In a welt-butting machine, the combination with welt butting knives of a member constructed and arranged to engage a shoe in the machine and to hold the shoe against movement in the direction of the welt-butting cut, and means for moving said member forwardly of the shoe after the welt-butting operation thereby to eject the shoe from the machine.
41. In a welt-butting machine, the combination with welt-butting knives and crease finders for supporting the welt for the butting operation, of means for moving the crease finders widthwise of a shoe in the machine to and from welt supporting position and an ejector for moving the shoe forwardly thereof out of the machine after the welt has been butted and while the crease finders are retracted.
42. In a shoe machine, a member constructed

and arranged to move with a shoe lengthwise thereof, an abutment for arresting movement of said member with the shoe thereby to position the shoe lengthwise thereof relatively to the 5 operating parts of the machine, means for adjusting said abutment lengthwise of the shoe, means for indicating the adjustment of said abutment in terms of shoe sizes, and an actuator for moving said abutment forwardly of the shoe to 10 eject the shoe from the machine.

43. In a welt-butting machine, welt-butting cutters including a pair of shear members, tack drivers a plurality of which are positioned at each side of the shoe for securing the margin 15 of the upper in the region of the welt butts to the insole, and means for individually adjusting the tack drivers widthwise of the shoe.

44. In a welt-butting machine, welt-butting knives, a holddown constructed and arranged to 20 engage the rear portion of the bottom of a shoe in the machine, shelves extending outwardly from the holddown and covering the rear portion of the shoe bottom, said shelves providing depositorys for receiving the waste ends of the 25 welt from the knives.

45. In a welt butting machine, a knife for butting one end of the welt of a welted shoe, means for moving the knife toward the toe end of the shoe in an inclined path to an intermediate 30 position, means for moving the knife from its intermediate position in a path substantially perpendicular to the shoe bottom to its cutting elevation, a rocking wiper member which travels with the knife and is constructed and arranged 35 for movement generally endwise of the knife to remove foreign matter therefrom, and means for operating said wiper member.

46. In a shoe machine, a work support movable heightwise of a shoe supported thereon, a 10 shoe bottom engaging member for positioning the shoe heightwise thereof in the machine, mechanical means for moving the work support to bring the shoe bottom into engagement with said member, and hydraulic means constructed and 45 arranged to operate after the shoe bottom has engaged said member to hold the work support against reverse movement.

47. In a shoe machine, a shoe support, mechanical means for moving the support heightwise 50 of a shoe thereon to position the shoe at a predetermined elevation, and hydraulic means which is inoperative during the heightwise movement of the support and which operates after the support has positioned the shoe to lock the support against return movement.

48. In a shoe machine, a support for a shoe, said support being constructed and arranged to 55 permit free movement of the supported shoe in any direction in a plane common to the rear portion of the shoe bottom, mechanical means for moving the support heightwise of the shoe to locate the shoe in a predetermined position heightwise thereof, and hydraulic means constructed and arranged to operate after the shoe 60 has been so located to lock the support against return movement.

49. In a shoe machine, a shoe support freely 65 movable lengthwise and widthwise of a shoe supported thereon, means for moving the support heightwise of the shoe, and means for locking the support against movement either lengthwise or widthwise of the shoe.

50. In a shoe machine, a shoe support freely 70 movable lengthwise and widthwise of a shoe supported thereon, means for moving the support

heightwise of the shoe, and a locking member operable at the will of the operator to lock the support against movement either lengthwise or widthwise of the shoe.

51. In a shoe machine, a shoe support constructed and arranged to receive and support any one of a plurality of shoe last engaging members thereon, and means on the support for orienting the shoe last engaging member thereon relatively to the operating parts of the machine. 10

52. In a shoe machine, a shoe support comprising upper and lower members relatively adjustable heightwise of a shoe supported thereon, the upper member being constructed and arranged to 15 receive and support any one of a plurality of shoe engaging members, means in the upper member for yieldingly supporting a shoe engaging member thereon, and means in said upper member for positively supporting the shoe engaging member. 20

53. In a shoe machine, a shoe support, means for moving the support upwardly to position a shoe thereon heightwise in the machine, a hydraulic lock for holding the support against 25 downward movement, a valve for the lock, and automatic means for opening the valve to permit downward movement of the support.

54. In a shoe machine, a shoe support, an actuator, connections from the actuator for lifting 30 the support, a hydraulic lock for holding the support against downward movement, a valve for said lock, and connections from the actuator for operating said valve.

55. In a shoe machine, a shoe support, an actuator, connections from the actuator for lifting 35 the support, means for pounding a shoe supported on the support, a hydraulic lock for holding the support against downward movement during the pounding operation, a valve for said lock, and 40 connections from the actuator for closing the valve before the pounding operation and opening it after the pounding operation.

56. In a shoe machine, a shoe support, an actuator, connections from the actuator for moving 45 the support upwardly, a holddown constructed and arranged to engage the bottom of a shoe on the support to limit upward movement of the support by the actuator, operating means constructed and arranged to exert downward pressure against 50 the supported shoe, a hydraulic lock for holding the support against downward movement during the application of downward pressure to the supported shoe, a valve for said lock, and automatic means for operating said valve. 55

57. In a shoe machine, a shoe support, a lifter for moving the support upwardly, a hydraulic lock for holding the support against downward movement, said lock comprising a reservoir connected to the lifter, a fixed hollow piston in the 60 reservoir, a valve for said lock, an actuator, connections from the actuator for operating the lifter, and connections from the actuator for operating the valve.

58. In a shoe machine, fastening inserting 65 means for securing the overlasted margin of a shoe in the machine to the insole including a member through which fastenings are driven, means for pressing said member laterally against the shoe bottom before the fastenings are driven, 70 and means for thereafter pounding said member against the shoe bottom.

59. In a shoe machine, means for inserting fastenings for securing the overlasted margin of a shoe in the machine to its insole including a 75

- member through which fastenings are driven, means for pressing said member laterally against the shoe bottom before the fastenings are driven, and means for pounding said member against the shoe bottom simultaneously with the driving of the fastenings.
60. In a shoe machine, means for inserting fastenings in a shoe bottom comprising a slide, a fastening driver for driving fastenings through an opening in the slide, a carrier for the slide, yielding means for holding the slide at the limit of its movement on the carrier toward the shoe bottom, means for moving the carrier toward the shoe bottom to bring the slide against the shoe bottom and to compress said yielding means thereby to press the slide against the shoe bottom, and means for thereafter pounding the slide against the shoe bottom.
61. In a shoe machine, tack-driving mechanism comprising a slide, a carrier therefor movable toward the plane of the bottom of a shoe in the machine, a tack driver constructed and arranged to operate through an opening in the slide, an actuator for the driver, a latch for holding the actuator retracted, means operated by movement of the carrier toward the shoe bottom to press the slide against the shoe bottom, and means operated by further movement of the carrier toward the shoe bottom to disengage the latch from the actuator.
62. In a shoe machine, tack-driving mechanism comprising a slide, a carrier therefor movable toward the bottom of a shoe in the machine, a tack driver constructed and arranged to operate through an opening in the slide, an actuator for the driver, a latch for holding the actuator retracted, means operated by movement of the carrier toward the shoe bottom to press the slide against the shoe bottom, means operated by further movement of the carrier toward the shoe bottom to disengage the latch from the actuator, a spring for operating the actuator, and means operating during movement of the carrier away from the plane of the shoe bottom to energize said spring.
63. In a shoe machine, tacking and pounding mechanism comprising a slide, a carrier in which the slide is mounted for movement toward the bottom of a shoe in the machine, means for moving the carrier in said direction, means operated by movement of the carrier for pressing the slide against the shoe bottom, a tack driver constructed and arranged to operate through an opening in the slide, an actuator for the driver, a latch for the actuator, a tripping member for unlatching the actuator, and an abutment on the slide for receiving the thrust of the driver after the tack has been driven.
64. In a shoe machine, tacking and pounding mechanism comprising a slide, a carrier in which the slide is mounted for movement toward the bottom of a shoe in the machine, means for moving the carrier in said direction, means operated by movement of the carrier for pressing the slide against the shoe bottom, a tack driver constructed and arranged to operate through an opening in the slide, an actuator for the driver, a latch for the actuator, a tripping member for unlatching the actuator, an abutment on the slide for receiving the thrust of the driver after the tack has been driven, a head in which the tacking and pounding mechanism is mounted, a source of motive power remote from the head, and connections therefrom to the carrier constructed and arranged to permit swinging movement of the head.
65. In a shoe machine, a plurality of fastening driving actuators, a driven slide for operating one of said actuators, operating connections from said slide to one of the actuators, and operating connections from that actuator to another actuator, said operating connections being constructed and arranged to permit individual adjustment of the actuators widthwise of a shoe in the machine.
66. In a shoe machine, a plurality of fastening driving actuators, a driven slide for operating said actuators, a head in which the slide and the actuators are mounted, a source of motive power remote from the head, connections therefrom to the slide constructed and arranged to permit swinging movement of the head, and means for individually adjusting the tacker actuators widthwise of a shoe in the machine.
67. In a shoe machine, tack-driving mechanism comprising a tack driver, tack-holding members which by their engagement with each other provide a pocket for the reception of a tack to be driven, one of said members being readily accessible, and means for moving the accessible member to expose a tack in said pocket and to permit its removal from the machine.
68. In a shoe machine, tack-driving mechanism comprising a driver, a guide for the driver, mechanism for holding a tack to be driven comprising a pair of fingers mounted in said guide and constructed and arranged to provide a pocket for a tack to be driven, holding means for holding the fingers against abutments provided in the guide to position the tack pocket in alignment with the driver.

ERIC A. HOLMGREN.

CERTIFICATE OF CORRECTION.

Patent No. 2,202,005.

May 28, 1940.

ERIC A. HOLMGREN.

It is hereby certified that error appears in the printed specification of the above numbered patent requiring correction as follows: Page 4, first column, line 9, after the word "rear" insert --end--; page 8, second column, line 27, before "firmly" insert --shoe--; and that the said Letters Patent should be read with this correction therein that the same may conform to the record of the case in the Patent Office.

Signed and sealed this 1st day of October, A. D. 1940.

(Seal)

Henry Van Arsdale,
Acting Commissioner of Patents.
